CARRIAGE-RETURN MECHANISM.

1,107,530.

Specification of Letters Patent. Patented Aug. 18, 1914

Application filed November 23, 1911, Serial No. 662,009. Renewed July 25, 1912. Serial No. 711,577.

To all whom it may concern:

Be it known that I, GEORGE W. KNOLL, a citizen of the United States, residing at Chicago, in the county of Cook and State 5 of Illinois, have invented new and useful Improvements in Carriage-Return Mechanism, of which the following is a specification.

This invention relates to typewriters, and 10 one object of the invention is to provide improved mechanism, under the control of the operator, for speedily returning the carriage of the typewriter to the starting point of a new line.

Another object is to provide improved 15 carriage return mechanism with line-spacing mechanism associated therewith and adapted to be set in motion at any point on the line, by means of a carriage return 20 key lever, and thereafter automatically arrested at the starting point of a new line.

Another object is to provide a simple 25 form of cushioning device in connection with the carriage return mechanism to prevent jarring between the carriage and typewriter frame when the carriage is returned.

Another object is to provide the carriage 30 return mechanism with a continuously running motor for effecting the movement of the carriage, and with clutch mechanism, operated by a carriage return key lever for 35 coupling the motor with the carriage in such manner that it may propel the same toward its starting point.

Other objects and advantages will appear 40 in the course of this specification and with all of said objects and advantages in view, this invention consists in the several novel features hereinafter set forth and claimed.

The invention is clearly illustrated in the drawings furnished herewith, in which:

Figure 1 is a plan of a standard form of 45 "Remington" typewriter, stripped of most of its operating mechanism, and showing the preferred form of my improved carriage-return applied thereto. Fig. 2 is a side elevation of the parts seen in Fig. 1, looking in the direction of the arrow 2 in Fig. 1. Fig. 3 is a detail front elevation 50 of a fragment of the typewriter frame, showing a carriage return key lever in cross section and showing in front elevation a guide and returning spring for the key lever. Fig. 4 is a view in rear elevation of 55 the parts seen in Figs. 1 and 2, with the

motor and motor carrying bracket cut-away on the line 4-4 of Fig. 2. Fig. 5 is a detail fragmentary rear view of certain bars carried by the typewriter carriage, certain portions of the clutch releasing mechanism 60 and carriage returning mechanism, the view being taken from the line 5-5 in Fig. 1, and looking in the direction of the arrows. Fig. 6 is a detail plan view of the left-hand portion of the mechanism illustrated in Fig. 5. 65 Fig. 7 is a detail view, illustrating the connections between the carriage shifting bar and the line-spacing mechanism of the typewriter, the view being partly in side elevation and partly in longitudinal section taken 70 on the line 7-7, Fig. 1. Fig. 8 is a detail vertical section of the clutch mechanism, the line of section being indicated at 8-8 in Fig. 4. Fig. 9 is a detail plan of a clutch 75 lever and adjacent parts. Fig. 10 is a detail front elevation of a fragment of the typewriter frame, the carriage, and a certain cushioning device for taking up the jar between the carriage and frame.

One form of the invention is illustrated 80 in the drawings to show its application to a standard form of "Remington" typewriter, and as is well understood to those skilled in the art to which this invention pertains, the typewriter frame A has mounted thereon a traveling carriage B, guided to move on rails a, a¹, supported on top of the typewriter frame. Typewriters of this kind are provided with suitable mechanism for printing upon a sheet of paper carried 85 by a platen or roller b, revolvably secured in the carriage and having a line-spacing lever b¹ connected to turn the platen by means of mechanism including a pawl b², adapted to engage with a toothed disk b³, 90 fast on the axle of the platen. The construction and operation of the parts mentioned are well known and understood by those skilled in the art. In the form of 95 "Remington" typewriter illustrated in the drawings, tabulating mechanism is associated therewith, and as is well known, a tabulator rack bar C is secured to and supported by brackets c, c¹, fastened to the rear end of the carriage B, and rigidly connecting the tabulator bar C with the carriage B.

In the form of carriage return mechanism chosen to illustrate its application, a rack bar 11 is slidably connected to the carriage 100 and is arranged to be propelled by a motor 110

12 in the direction of the arrow *x* (Fig. 1), to effect the return of the carriage to its starting point. The motor 12 is here shown in the form of an electric motor supported 5 from the frame of the typewriter as by a bracket 13, secured to the rear end of the frame by screws 14. The motor rests upon screws or bolts 15, and is secured to the bracket 13 by bolts 16, whereby the motor 10 may be adjusted to properly position the same with respect to other members of the connections between the motor and carriage.

The rack bar 11 is shown as located below and in front of the tabulator bar C, and supported on the underside of the brackets *c*, *c*¹ 15 by rollers 17 supported by and projecting down from the brackets *c*, *c*¹, and turning in longitudinally extending grooves 18 formed in the sides of the bar 11 (Figs. 4, 5 20 and 7). This arrangement affords one means for slidably connecting the bar 11 with the carriage, so that it has a limited amount of movement relatively to the carriage, and said bar 11 is formed with shoulders 19, 20 arranged to strike the brackets *c*, *c*¹ 25 at the limits of its strokes with respect to the carriage. This sliding is utilized to effect the line-spacing in the form of the invention shown. When the bar 11 has been 30 moved from the position indicated in Fig. 4 to that indicated in Fig. 5, the shoulder 19 strikes the bracket *c*¹ so that further movement of the bar toward the left, as viewed in said figures, will move the carriage in the 35 same direction.

It is to be observed that the shoulder 19 of the bar 11 strikes against a rigid element of the carriage, thereby insuring positive movement of the carriage, and effecting 40 such movement by means of substantial elements, thus eliminating wear and tear to a great degree. A spring 21 attached to the bar 11 and bracket *c* retracts the bar 11 after the carriage has been returned to its starting point.

In the preferred form of connections between the motor and carriage two contacting friction disks 22, 23 carried by shafts 24, 25 are employed, one being loose on its 50 shaft, and the other being fast on its shaft. As here shown the disk 22 is fast on the motor shaft 24, while the disk 23 is loose upon its shaft 25 (Fig. 8), but arranged to be coupled thereto by clutch mechanism 26. 55 The disk 22 is preferably of smaller diameter than the driven disk 23 to reduce the speed, and said disk 22 may be shifted back and forth on the motor shaft 24 to increase or decrease the speed of the disk 23. The 60 shaft 25 is journaled in brackets 25^a, 25^b secured respectively to the frame A and the bracket 13.

The clutch mechanism 26 may be of any simple form, and the one illustrated comprises 65 a clutch member in the form of a

collar 27 having a conical inner bearing face 28 arranged to be moved into frictional contact with the conical face 29 of a second clutch member in the form of a cone 30 projecting up from the disk 23. The clutch collar 27 is pivoted transversely of the shaft 70 25, as by a pin 31 secured in the shaft and extending into vertical slots 32 formed in the neck 33 of the collar 27, thus permitting of a limited vertical movement of said collar with respect to the shaft 25.

A clutch lever 34 (Figs. 4 and 9), fulcrumed upon a bracket 35, connects with the clutch collar 27 at one end, and with a link 36 at its other end, said lever 34 being forked to straddle the neck of the collar and connected thereto by a ring 37 seated in an annular groove in the neck and pinned to the fork of the lever. The lower end of the link 36 is connected to the rear end of a carriage return key lever 38 (Figs. 1 and 2) fulcrumed upon a bracket 39 located adjacent its connection with the link 36; the carriage return key lever extends toward the front of the machine, and at a point adjacent the type keys of the machine is provided with a finger key 38^a. The front end of the carriage return key lever 38 is guided to move in a vertical plane by a plate 40 secured to the typewriter frame and having a vertical slot in which the lever 38 plays.

A spring 41 connected to the plate 40 and lever 38 acts to raise the front end of the lever to normal position after it has been depressed and released. It is obvious that by depressing said key 38^a, the link 36 is raised and the clutch lever 34 rocked in the direction of the arrow in Fig. 4, thereby forcing the clutch collar down upon the cone 30 and locking the shaft 25 with the disk 23. Said disk being loose upon its shaft, normally rests loosely upon the disk 22, and is continuously driven idly by the motor through frictional engagement with the disk 22. The frictional pressure between the clutch members and also between the rotating disks 22 and 23 is controlled by and varies with the pressure on the finger key 38^a.

Fast on the upper end of the shaft 25 is a bevel pinion 41 that meshes with a bevel gear 42 fast upon a horizontal counter shaft 44 journaled in a bracket 45 secured to the top of the typewriter frame. A toothed wheel 46, fast upon said counter shaft 44, meshes with the rack bar 11 and propels said bar and the carriage when set in motion by the motor. As the carriage is being advanced, during operation of printing, the toothed wheel is turned in a retrograde direction by said bar, and consequently its shaft, the gears 41, 42, shaft 25 and clutch collar 27 are turned back to normal position.

It is to be observed that so long as the key 38^a is held down, the clutch 26 remains in clutched condition, and as it is particularly 130

desirable that the carriage be arrested at the starting point of a new line, and the clutch disconnected automatically at such period, improved means are provided for accomplishing this result.

As shown, the tabulating bar C has projecting down therefrom a finger or other trip device 47 here shown as capable of being secured in place on said tabulating bar 10 at any of the notches thereon, thus determining the point at which the carriage is to be arrested at the end of its return movement. Said finger or trip device is arranged to engage and depress an arm 48 that lies in its path of movement, said arm being fast upon a rock shaft 49 journaled in a bracket 50 supported on top of the typewriter frame (Figs. 1, 4 and 5). On said rock shaft 49 is secured a second arm 51 that is operatively connected with the clutch lever 34 by a link 52, whereby whenever the free end of said arm 48 is depressed, the end of the arm 51 and the link 52 is raised thus raising the forked end of the clutch lever 34, and disconnecting the clutch collar from the cone.

The cushioning device is best seen in Figs. 1 and 10, and as shown comprises a bent finger 53 adjustably secured to the scale bar 54 of the carriage and arranged to strike 30 against a projecting pin 55 of the cushioning device. Said pin is slidably mounted in a bracket 56 stationarily supported on the front of the rail a^1 of the typewriter frame. As shown the pin 55 is guided to move longitudinally in slots in said bracket and has a limited amount of movement therein controlled by a spring 57 secured to said pin 55 and to the bracket 56. The tension of the spring arrests the momentum of the carriage as the bent finger 53 strikes the pin 55 and extends the spring 57. The fingers 47 and 53 are set upon the bars C and 54, respectively, so that the finger 47 may disconnect the clutch at or about the time that the finger 53 strikes the pin 55.

The line-spacing is effected by a simple mechanism operated from the bar 11, which bar is arranged to shift a link 58, that connects with the pawl b^2 . In the form shown 50 the end of the bar 11 carries a plate 59 having an angularly disposed bearing edge 60 that bears against a roller 61 carried by the link 58 (Figs. 5, 6 and 7). Fig. 1 shows the bar 11 and bearing plate 59 in normal position relatively to the roller 61, and Figs. 5 and 6 show it shifted to effect the shifting of the link 58. A clip 62, secured to the bar C, overhangs the link 58 to guide its movement in a straight line. The link is preferably made in two pieces connected by a bolt threaded in one piece and extending through a slot in the other, whereby if desired the two parts of the link may slide one upon the other by unscrewing the bolt. This is done 60 when it is desired to move the platen more

than one tooth at a time with the line-spacing lever b^1 .

In the operation of the carriage return mechanism, the operator sets the fingers 47 and 53 at the desired points to bring the carriage to a stop at the place determined upon. A line having been written, the operator depresses the key 38^a, thereby coupling together the two members of the clutch mechanism, and at the same time lowering the link 52 and swinging the arm 48 upward and into the path of the finger 47. The motor, being in continuous operation, immediately sets the gearing between the disk and bar 11 in motion, thereby first shifting the bar 11 over until the stop 19 strikes the bracket c^1 , and operates the line-spacing mechanism after which the further movement of the bar 11 causes the carriage to move therewith toward the starting point until the finger 47 strikes and depresses the arm 48, thereby unclutching the collar from the cone of the clutch mechanism and returning the key lever 38, although the operator still has his finger on the carriage return key 38^a. Simultaneously with the disconnection of the clutch members, the bent finger 53 strikes the pin 55 of the cushioning device and the momentum of the carriage is arrested by the spring 57 as the carriage comes to a full stop at the beginning of a new line.

It is obvious that the operator may, if so desired, manually return the carriage by using the line-spacing lever b^1 without interfering with the mechanical carriage return mechanism, which is an important feature in devices of this character. By reason of the fact that the motor is continuously running, the carriage is returned quickly and with a steady even motion; no jars or shocks are occasioned by the use of the present form of carriage return mechanism, and this is a very important consideration in machines of this type, as it eliminates the danger of injury and heavy wear upon the machine.

Variations may be resorted to within the scope of the invention, and portions of the improvements may be used without others.

Having thus described my invention, I claim:

1. In combination, a typewriter frame, a carriage slidably mounted thereon, a rack bar operatively connected to said carriage, a toothed wheel meshing with said rack bar, a continuously running motor, a pair of friction disks, one of which is directly driven by said motor, a shaft operatively connected to said toothed wheel, friction clutch mechanism between said shaft and the other friction disk, and a carriage return key lever operatively connected with the clutch mechanism.

2. Carriage return mechanism comprising a rack bar arranged to be secured to a typewriter carriage, a toothed wheel meshing

with said rack bar, a shaft operatively connected with said toothed wheel, a motor driven disk loosely mounted upon said shaft, clutch mechanism for clutching together 5 said disk and shaft, and a carriage return key lever operatively connected with said clutch mechanism.

3. Carriage return mechanism comprising a rack bar arranged to be secured to a typewriter carriage, a toothed wheel meshing with said rack bar, a vertically extending rotary shaft, power transmitting connections between said shaft and toothed wheel, a motor driven disk on said shaft, clutch mechanism for coupling said shaft to said disk, a clutch lever connected to one member of 10 said clutch mechanism, a carriage return key lever, and a link connecting said clutch lever with said carriage return key lever.

20 4. Carriage return mechanism comprising a rotary shaft, power transmitting mechanism arranged to translate the rotary motion of said shaft into a rectilinear movement of a typewriter carriage, a friction disk on said shaft, a motor driven disk frictionally engaging and driving said first-named disk, a clutch to transmit the motion of said disks to the said shaft, said clutch comprising a collar on said shaft and rotatively connected 25 therewith and a clutch cone on said first-mentioned disk, a carriage return key lever, and operative connections between said lever and clutch collar for engaging the latter with the clutch cone.

30 5. Carriage return mechanism comprising a motor driven shaft, clutch mechanism, a carriage return key lever to operate the clutch mechanism for operatively coupling said shaft with its prime mover, power transmitting mechanism for translating the 35 rotary motion of said shaft into a rectilinear movement of a typewriter carriage, a trip member secured to and moving with said carriage, and clutch releasing mechanism 40 having an element lying in the path of said trip member and arranged to be actuated thereby to unclutch the clutch mechanism.

45 6. Carriage return mechanism comprising a motor driven shaft, clutch mechanism, a carriage return key lever to operate the clutch mechanism for operatively coupling said shaft with its prime mover, power transmitting mechanism for translating the 50 rotary motion of said shaft into a rectilinear movement of a typewriter carriage, a trip member secured to and moving with said carriage, a rocking element having one arm lying in the path of said trip member, and a link connected to another arm of said 55 60 rocking element and connected with one member of the clutch mechanism.

65 7. Carriage return mechanism comprising a motor driven shaft, clutch mechanism, a carriage return key lever to operate the clutch mechanism for operatively coupling

said shaft with its prime mover, power transmitting mechanism for translating the rotary motion of said shaft into a rectilinear movement of a typewriter carriage, a trip finger adjustably secured upon a bar rigidly secured to said carriage, and clutch releasing mechanism having an element lying in the path of said trip finger and arranged to be actuated thereby and therewith to unclutch the clutch mechanism.

70 8. In combination, a typewriter frame, a carriage thereon, a platen rotatively mounted on said carriage, pawl and ratchet line-spacing mechanism for said platen, a rack bar mounted on said carriage and having a limited amount of sliding movement relative thereto, a toothed wheel meshing with said rack bar for moving the same and its carriage in one direction, operative connections between said rack bar and line-spacing pawl, a continuously running motor, gearing comprising a friction clutch between the motor and said toothed wheel, and a key to actuate said clutch to connect the 75 motor to drive said wheel.

90 9. In combination, a typewriter frame, a carriage thereon, a platen rotatively mounted on said carriage, pawl and ratchet line-spacing mechanism for said platen, a shoul- 95 dered rack bar, brackets secured to the carriage and supporting said rack bar, said rack bar having a limited amount of lost motion with respect to said brackets at the limit of its lost motion, a power driven toothed wheel meshing with said rack bar and arranged to move the same in a direction to return the carriage, a bearing plate carried by said rack bar and having an angularly disposed bearing face, and a link connected with said pawl and having a roller arranged to be engaged by said bearing face of the plate.

100 10. In a typewriting machine, the combination with a carriage having a letter-feeding movement, of a motor for returning said carriage, a clutch intermediate said carriage and motor, a key arranged to close said clutch, and an arm moved by said returning carriage to positively release said clutch by the power supplied through the carriage.

110 11. In a typewriting machine, the combination with a carriage having a letter-feeding movement, of a constantly running motor for returning said carriage, a clutch intermediate said carriage and motor, a key arranged to close said clutch, and an arm moved by said returning carriage and operated by the power of the motor to positively release said clutch.

115 12. In a typewriting machine, the combination with a carriage having a letter-feeding movement, of a constantly running motor for returning said carriage, a clutch intermediate said carriage and motor, a key arranged to close said clutch, and an arm 120 125 130

operated positively by said returning carriage to positively release said clutch and positively return said key to its normal position.

5. 13. In a typewriting machine, the combination with a carriage having a letter-feeding movement, of a motor to return said carriage, a clutch intermediate said carriage and motor, a key arranged to close said clutch, an arm arranged to release said clutch, and an arm on said carriage arranged to move said first arm to release said clutch as the carriage returns to its starting point and to hold said clutch released over 15 several letter-spaces.

14. In a typewriting machine, the combination with a carriage having a letter-feeding movement, of a motor to return said carriage, a clutch intermediate said carriage and motor, a key arranged to close said clutch, an arm arranged to release said clutch, a rack on said carriage arranged to hold tabulator stops, and a stop member adjustable on said rack to move said arm to release said clutch as the carriage returns to the starting point, and to hold said clutch released over several letter-spaces.

15. In a typewriting machine, the combination with a carriage and a motor to return the carriage, of driving connections between the motor and carriage including frictional driving members in rolling contact, a clutch, a key to actuate the clutch and control the friction between said members, and means to automatically release the clutch and disconnect the carriage from the motor before the carriage has completed its return movement.

16. In a typewriting machine, the combination with a carriage and a motor to return the carriage, of driving connections between the motor and carriage comprising friction disks in rolling contact, a friction clutch member carried with one of the disks, a co-operating clutch member, and a key opera-

tively connected to said last-named clutch member to actuate the clutch and to vary the pressure between said disks in response to variations in pressure on said key.

17. In a typewriting machine, the combination with a carriage and a motor to drive the carriage forward, of a drive shaft, a rack and pinion forming a driving connection between said shaft and the carriage, a second motor to return the carriage, a clutch between said second motor and the drive shaft, a key to operate said clutch and connect the said second motor to the drive shaft, and means to automatically disconnect the carriage from the said second motor during 60 the return of the carriage.

18. In a typewriting machine, the combination with a carriage, a motor to drive it forward, and a second motor to return the carriage, of a drive shaft, key-operated 65 means to connect the drive shaft to said second motor, a rack and pinion between said drive shaft and the carriage, and means operated by said drive shaft to automatically disconnect said second motor from said 70 drive shaft during the return of the carriage.

19. The combination with a carriage and a motor to return the carriage, of a drive shaft, a driving connection between said 75 shaft and the carriage, gearing between said shaft and motor comprising a clutch, a key to operate the clutch and thereby connect the motor to the drive shaft, and means operated by said shaft to open said clutch and 80 restore the key during the return movement of the carriage.

In witness whereof, I have hereunto set my hand at Chicago, Cook county, Illinois, this 21st day of November 1911.

GEORGE W. KNOLL.
